Primary Examiner — Ian Simmons*Assistant Examiner* — Janice Lim(74) Attorney, Agent, or Firm — Seager, Tufte & Wickhem LLP(57) CLAIM

The ornamental design for a cosmetic jar, as shown and described.

DESCRIPTION

FIG. 1 is a perspective view of a cosmetic jar, showing our new design;

FIG. 2 is another perspective view thereof, shown with the cap removed;

FIG. 3 is a top plan view thereof;

FIG. 4 is a bottom plan view thereof;

FIG. 5 is a front elevation view thereof;

FIG. 6 is a rear elevation view thereof; and,

FIG. 7 is a left side elevation view thereof, and the right side view being a mirror image thereof.

The broken line portions show unclaimed subject matter only and form no part of the claimed design.
